UNITED STATES PATENT OFFICE.

COLUMBUS K. LASSITER, OF RICHMOND, VIRGINIA, ASSIGNOR TO NORMAN E. WOODS,
OF PATERSON, NEW JERSEY.

AUTOMATIC SPACING AND PUNCHING MACHINE.

1,375,302.

Specification of Letters Patent. Patented Apr. 19, 1921.

Application filed April 7, 1920. Serial No. 371,977.

To all whom it may concern:

Be it known that I, COLUMBUS K. LASSITER, a citizen of the United States, residing at Richmond, in the county of Henrico 5 and State of Virginia, have invented new and useful Improvements in Automatic Spacing and Punching Machines, of which the following is a specification.

This invention relates to certain new and 10 useful improvements in spacing and punching machines, such as are used for punching holes at determined intervals in sheet metal, and one object of my invention is to provide a machine of this character 15 which, when set into action, will operate automatically to feed the sheet supporting table forward intermittently and punch the sheet at proper intervals until the required number of holes are formed, and 20 then reverse the direction of motion of the table and return it to starting position.

A further object of my invention is to provide simple, reliable and efficient means whereby the degree of intermittent feed motion of the table may be varied and the 25 punching intervals of the punch regulated and governed accordingly, and also to provide a construction of means whereby any desired number of holes may be punched 30 and the automatic stopping of the feed motion of the table and return of the table to starting position effected, regardless of the length of the sheet.

A still further object of my invention is 35 to provide a drive mechanism in frictional driving engagement with the table for forward and reverse motions, and a feed mechanism operating to positively control and insure the intermittent forward feed motion of the table to properly spaced punching positions, and to hold the same in such 40 positions, whereby the holes may be accurately punched at prescribed intervals without tendency to distort the sheet.

A still further object of my invention is 45 to provide drive and feed mechanisms of the character described whereby, in the event that the table strikes a solid object, the drive and feed mechanisms will be automatically thrown out of action to prevent possible damage to the sheet or parts of the 50 apparatus.

A still further object of my invention is to provide an automatic spacing and punching machine which is simple of construction, reliable and efficient in action, and readily and conveniently adjustable for operation to vary the punching intervals and number of punching actions according to the distance between holes to be punched 60 and number of holes to be punched in a sheet of given size.

With these and other objects in view, the invention consists of the novel features of construction, combination and arrangement 65 of parts, hereinafter described and claimed, reference being had to the accompanying drawings, in which:

Figure 1 is a top plan view of the machine. 70

Fig. 2 is a view in elevation of the machine looking from the side opposite that on which the punch mechanism is located.

Fig. 3 is a view similar to Fig. 2 of a portion of the machine on an enlarged 75 scale.

Fig. 4 is a vertical transverse section through the machine.

Fig. 5 is a view similar to Fig. 3 viewed from the opposite side of the machine. 80

Fig. 6 is a side view of the punch with parts appearing in section.

Fig. 7 is a longitudinal section through the sliding clutch member on the main drive shaft. 85

Fig. 8 is a sectional elevation of the gear shifting lever and table drive gearing, showing in full and dotted lines, respectively, the lever and gearing in reverse and forward drive positions. 90

Fig. 9 is a detail view of the screw-shaft, nut and coacting parts of the intermittent feed mechanism.

Fig. 10 is a longitudinal section through the ratchet drive gearing of the intermittent feed mechanism. 95

Fig. 11 is a section on the lines 11—11 of Fig. 10.

Fig. 12 is a detail section on the lines 12—12 of Fig. 5. 100

Fig. 13 is a perspective view of elements of the manually set and automatically released controlling mechanism.

Fig. 14 is a view similar to Fig. 8, show-

ing the gear shifting lever in neutral position.

In the practical embodiment of my invention in the form disclosed, 1 designates a horizontal supporting frame of suitable length and width, which frame forms a support for a traveling work table or carriage 2, and includes in its construction parallel longitudinal side bars 3, said frame being mounted upon standards or uprights 4 resting upon a floor or other foundation. Disposed at one side of said frame is a pedestal 5 arranged in proximity to one of the side bars 3 and rigidly fastened thereto if desired.

On the table 2 is rested and clamped the metallic sheet to be punched, said sheet being firmly held in position thereon by and between relatively fixed and adjustable clamps 6 and 7. These clamps are designed to be respectively engaged with the opposite end edges of the sheet, the clamp 7 being adjustable along a slot 8 to enable sheets of different lengths to be clamped. The clamps further serve as gages to regulate the setting of the sheet for the punching of a row of holes with due regard to the arrangement of such holes with respect to the ends of the sheet, and also to properly control the table feeding and punching actions accordingly. As shown, the clamp 7 carries a trip member 9 for certain automatic controlling actions, as hereinafter described.

The table is directly mounted for travel upon transversely arranged pairs of rolls 10, 11, 12 and 13 arranged at regular intervals apart along the length of the frame. Of these, the outer pairs of rolls 10 and 13 support the ends of the table at its extremes of movement and said rolls may be mounted on the frame in any suitable manner, while the intermediate rolls 11 and 12 serve as friction drive elements of a table feed and return mechanism. The rolls 11 and 12 are, therefore, fixedly mounted on shafts 14 and 15 journaled on the frame and said shafts are connected for movement in unison by a sprocket chain or belt 16 passing around sprocket wheels or pulleys 17 on said shafts. In the present instance I have shown the use of plain surfaced rollers at one side of the frame and grooved rollers at the opposite side of the frame engaged by horizontal and transverse track members 18 and 19 formed by the side bars of the table frame, said grooved rollers serving to guide and hold the carriage against lateral displacement, but any suitable means for this purpose may be employed.

Carried by the pedestal 5 is a frame 20 supporting the power and punch mechanisms, consisting of an electric or other suitable motor 21 the shaft of which carries a gear pinion 22 meshing with a gear 23 loosely mounted on a driving shaft 24, said

gear 23 being in operation continuously driven from the motor. The shaft 24 is coupled by suitable crank mechanism at its forward end to a reciprocating punch 25 arranged for co-operation with a stripper 26 and anvil 27, between which anvil and stripper the edge of the sheet to be punched lies when the table is in fixed or punching position and travels when the table is in motion. The ratio of the gears 22 and 23 is such that while the motor shaft may be driven at comparatively high speed the drive shaft 24 will be driven at a relatively slow speed. Fixed to the loose primary drive gear 23 is a drive pulley 28 which is connected by a belt 29 with a pulley 30 on a transverse countershaft 31 journaled on the table, said belt gearing thus being continuously driven by and with the gear 23 when the motor 21 is in action, while the drive shaft 24 remains in a state of rest until intermittently operated at prescribed periods, as hereinafter described. Fixed to the shaft 31 is a gear 32 normally in mesh with gears 33 and 34 carried by a gear shifting lever 35 loosely mounted on the shaft 31 for swinging movements in a direction longitudinally of the frame 1 between table driving, table reversing and neutral positions. The gear 33 is provided for transmitting forward driving motion, through an intermediate gear 36, from the gear 32 to a gear 35' on the shaft 14, while the gear 34 is provided for transmitting reverse or backward driving motion from the gear 32 to the gear 35'. The gears mentioned constitute the elements of gear trains for driving the table through the friction drive mechanism both forwardly or on its feed motion and backwardly or on its return motion to starting position. When the lever 35 is in the position shown in Figs. 1, 2 and 3, and also shown in full lines in Fig. 8, the pinion 36 is in mesh with the gear 35' for transmitting forward drive motion to the carriage, while when the lever 35 is in the position shown in dotted lines in Fig. 8, the pinion 36 is withdrawn from engagement with the gear 35' and the pinion 34 thrown into engagement therewith for transmitting motion through the friction drive mechanism to move the table backward on its reverse motion to starting position. It will be observed that the lever 35 is movable to positions at equal angles to the perpendicular for the forward driving and reverse driving motions, and that it has an intermediate or perpendicular position, as shown in full lines in Fig. 14, in which both gears 34 and 36 are out of mesh with the gear 35' to stop the motion of the friction drive mechanism, so that the table may be allowed to remain in a state of rest in its starting position as long as desired. The lever 35 is provided with a slotted T-shaped

head 36' forming a guideway for a rolling counterweight 37, which is movable to reverse positions at opposite ends of said guideway to maintain the lever in starting and reverse positions. The shaft of this weight which travels in the guide slot is also adapted to engage a seat recess 38 at the center of the guideway to dispose the weight in a mid-way or neutral position, thus preventing tilting of the lever beyond center in either direction when the lever is in its neutral or gear cut-out position. It will thus be understood that when the gear 36 is in mesh with the gear 35' the friction wheels or rollers 11 and 12 will be driven to transmit forward driving motion to the table 2; that when said gear is out of mesh with the gear 35' and the gear 34 meshes with the gear 35' the friction rollers 11 and 12 will be driven in a reverse direction to move the table backwardly, and that when both gears 34 and 36 are out of mesh with the gear 35' the friction drive rollers 11 and 12 will remain stationary.

25 Journaled upon the frame 1 is a longitudinally extending screw-shaft 39 carrying at one end a beveled gear pinion 40 meshing with a similar gear pinion 41 on a shaft 42. This shaft 42 is adapted to be driven by intermittent feed mechanism from the shaft 24 at determined periods. Provided for co-operation with the shaft 39 is a split traveler nut 43 comprising relatively movable nut sections 44 and 45 carried by lever arms 46 and 47 extending from head portions 48 and 49 formed on said nut sections. The lever arms 46 and 47 are crossed and pivotally connected at their crossing point to each other and to a supporting bracket 50 projecting from the table 2 by means of a pivot pin or member 51, whereby the nut sections 44 and 45 are pivotally mounted for swinging movements to move into and out of engagement with the screw-shaft 39. Above their pivotal point the lever arms are provided with extensions 52 and 53 perforated for the passage of a bolt 54 carrying adjusting and lock nuts 55 and 56. Encircling the bolt between the extension 53 and the 50 adjusting nut 55 is a coiled spring 57, acting on the lever arms 46 and 47 to urge the nut sections 44 and 45 into engagement with the screw-shaft 39. By means of the nuts 55 and 56 the tension of this spring 57 may be 55 regulated to govern the nut closing pressure of the spring and its resistance to nut opening movement, the nut 56 holding the nut 55 against tendency to displacement. Journaled upon the frame 1 in parallel relation 60 with and immediately above the screw-shaft 39 is a nut releasing element comprising a rock bar or shaft 58 of square or other angular form in cross section, which is movable through an arc of one-eighth of its revolution to bring two of its angular corner edges

into engagement with angular recesses formed in the faces of the heads 48 and 49, whereby to permit the nut sections 44 and 45 to be moved by the pressure of the spring 57 into engagement with the screw-shaft 39, 70 and said shaft 58 is also movable to a position to bring two of its opposite flat faces into engagement with the heads 48 and 49 to spread the nut sections 44 and 45 against the resistance of the spring 57, and thereby 75 release the nut from engagement with the screw-shaft. The screw-shaft and nut provide a positive feed mechanism intermittently operated to govern the degrees of forward feed motion of the table 2 between 80 punching positions. When the nut is in engagement with the shaft, and driving motion is imparted to the latter, the nut will be caused to travel a predetermined distance forward on the shaft so as to move the table, 85 irrespective of its driving motion under the action of the friction driving means, forward a certain distance and no more, and to hold the table in adjusted position firmly against movement while the sheet is being 90 punched. While the table is thus held stationary, for the determined period, by the screw-shaft and nut, the friction wheels 11 and 12 continue to turn but slip idly in engagement with the track rails 18 and 19, 95 their pressure on the rails serving, however, to insure accuracy of movement of the table by taking up any possible lost motion that may be due to wear on the screw-shaft and nut from continued service of the apparatus. 100 The nut remains in engagement with the screw-shaft and the latter is operated intermittently any predetermined number of times for successive punching actions, dependent upon the length of the sheet and 105 the number of holes to be punched therein, through the instrumentality of governing mechanism, whereby, after the required number or series of holes are punched, the nut is released, the punching and intermittent feed gearing thrown out of action, and the friction gearing thrown into action to reverse or return the table to starting position.

110 The intermittent feed mechanism employed for driving the shaft 39 comprises a crank arm 59 fixed to the rear end of the shaft 24 and carrying a crank or wrist pin 60 coupled to a vertically reciprocating and oscillating rack bar 61. This rack bar 61 115 is slidable through a guide casing 62 loosely mounted upon the rear end of the shaft 42 so as to rock or oscillate with said lever in its reciprocations under the action of the crank 59. The toothed surface of the rack bar 61 meshes with the peripheral teeth 63 of a spur gear 64 loosely mounted on the shaft 42 and provided upon one of its sides with an annular series of ratchet teeth 64', forming a clutch surface, said ratchet teeth 120

125 130

64' being adapted for engagement with corresponding ratchet or clutch teeth 65 upon a clutch head or disk 66 rigidly mounted on the shaft 42. The gear member 64 is slideable on the shaft 42 for movement of its ratchet or clutch face 64' toward and from the clutch face of the clutch head 66, a coiled spring 67 being provided to urge the gear 64 into clutching engagement in one 10 of its directions of rotation and to permit recession of said gear 64 and sliding of the sets of clutch teeth over one another on the reverse direction of rotation of said gear 64. A follower 68 and suitable adjusting 15 and check nuts 69 and 70 are provided for holding the parts in proper relative position and regulating the pressure of the spring. Thus it will be understood that on one-half the revolution of the crank 59 in 20 its orbit of movement the rack bar 61 will be moved in one direction to transmit motion to the gear 64 and through said gear and the clutch head 66 to the shaft 42, while on the remaining half revolution of 25 the crank arm 59 the rack bar 61 will be moved in the opposite direction or on its return stroke, in which it will reversely rotate the gear 64 without turning the shaft 42, as the clutch teeth 64' and 65 will slide 30 idly over each other. The crank mechanism which operates the punch from the shaft 24 and the intermittent feed gearing actuated by the crank 59 are so timed with relation to each other that during one-half of 35 the revolution of the shaft 24, while the table 2 is held fixed, the punch will be on its downward or working stroke, while the rack bar 61 is on its return or inactive stroke, while during the remainder of the 40 revolution of the shaft 24, and while the punch is being retracted on its up-stroke, the rack bar 61 will be on its working stroke to drive the shaft 42 to communicate motion to the shaft 39 to feed the table forward for 45 the next punching action. The crank or wrist pin 60 extends through a longitudinal slot 67' in the crank arm 59, which is formed with a longitudinal guideway 68' with which the slot connects, and said crank pin 50 is formed with a head 69' adjustable to different positions in the guideway along the length of the crank arm, whereby the effective radial length of the crank arm may be varied and the working stroke of the 55 rack bar 61 correspondingly varied. On the pin 60 is a clutch collar or sleeve 70' having a toothed face to engage teeth 71 upon the crank arm, whereby the crank pin may be fixed in adjusted position, a nut 72 being 60 provided for drawing the head 59 and sleeve 70' into clamping position, and the rack bar being fitted to turn loosely upon said sleeve. It will thus be understood that the action of the intermittent feed gearing 65 may be varied, by varying the effective

length of the working stroke of the rack bar 61, thus varying the degree of intermittent feed motion of the screw-shaft 39, so that the distance between punching positions of the carriage may be varied, allowing the holes in the sheet to be punched a greater or less distance apart according to circumstances or conditions within determined limits. 70

Feathered to slide upon and rotate with 75 the shaft 24 is a clutch collar 73 provided with a clutch pin 74 to engage a clutch pin 75 on the adjacent face of the pulley 28. When this clutch collar is free for action it is moved into clutching engagement with 80 the pulley 28 by a spring 76. The collar 73 is provided with a cam surface 77 for co-operation with a friction roller 78 revolvably mounted upon the upper end of a latch bolt or plunger 79 fitted for vertically sliding movements in a casing 80 on the frame 20. The latch bolt or plunger 79 is movable to locking position by a spring 81, and when disposed in such position the roller 78 is arranged to lie in the path of the cam 85 77. The arrangement of these parts is such that when the punch is retracted and the parts in normal or inoperative position, as shown in Fig. 6, the roller 78 will be engaged by the highest point of the surface 95 of the cam, thus holding the clutch collar 73 retracted and the spring 76 tensioned, the shaft 24 thus being disconnected from the drive gear 23 and the punch mechanism and intermittent feed mechanism held inoperative, while upon moving the locking bolt 90 downward and withdrawing the roller 78 from out of the path of the cam the clutch collar 73 will be freed for movement by the spring 76 to throw it into clutching engagement with the drive gear to drive the shaft 24 and the parts operated thereby for successive actions of the punch and intermittent feed mechanism as long as the locking bolt is held retracted. The lower end of the 100 locking bolt is pivotally coupled to a short crank arm 82 on a rock shaft 83 to which is connected a controlling lever 84, adapted to be manipulated by the operator of the machine to retract the locking bolt and set the 105 punch mechanism and intermittent feed mechanism into action. Also connected with the shaft 83 is a crank arm 85 coupled by a link 86 to a combined crank and latch arm 87 on the angular bar or rock shaft 58. 110 A second link 88 connects the crank arm 86 with one arm of a bell crank lever 89 fulcrumed on the frame 20, the other arm of which bell crank lever is connected by a 115 control bar or link 90 with the gear shifting lever 35. Through this system of controlling connections between the operating handle 83, the bolt 79, rock bar or shaft 58 and gear shifting lever 35, the bolt 79 may be retracted to throw the clutch member 73 120 125 130

into action to start the operation of the punch and intermittent feed mechanism and to simultaneously adjust the rock bar or shaft 58 to a position allowing the nut 43 to engage the feed shaft 39, while at the same time the lever 35 will be shifted from a neutral to a table starting position, in which pinion 36 is brought into meshing engagement with gear 35'. When, on the other hand, the bolt 79 is released for locking projection by its spring 81, so as to effect the retraction of the clutch member 73 and arrest the motion of the plunger and intermittent feed mechanism, the controlling connections just described will transmit motion to the crank arm 87 to adjust the bar 58 to nut spreading or releasing position, while the link 90 will be drawn upon to swing the lever 35 to carriage reversing position in which pinion 34 meshes with gear 35'. This automatic shifting action to throw the punch and intermittent feed mechanism out of operation, and simultaneously throwing the table reversing gearing into operation, is effected by the expansive action of the spring 81, which is made of sufficient strength for this purpose. The link 90 has a slip-joint or lost-motion connection with the lever 35, said connection comprising a headed pin or stud 91 engaging a slot 92 in the link. When the lever 35 is in forward feed position the stud 91 engages the outer end wall of the slot 92, as shown in full line positions of the lever illustrated in Figs. 3 and 8. This slot is of sufficient length to permit the lever 35 to be drawn positively to a position slightly beyond center on its movement to reverse position, the pin 71 then sliding toward the inner end wall of the slot 92 and such motion of the lever being completed by the rolling action of the counterweight 37 in an obvious manner. When the lever 35 is in reverse position, the lost-motion connection referred to permits it to be independently moved back to a midway or neutral position for throwing the friction drive mechanism out of operation, such motion of the lever 35 to neutral position being effected in the manner herein-after described.

When the lever 84 is adjusted to set the punch and intermittent feed mechanism for action, the crank arm 87 is moved into position for engagement by the latch end 93 of a pivoted latch lever 94 mounted on and extending transversely of the frame 1 in the path of movement of the trip member 9 carried by the adjustable work clamp 7, said latch lever being normally maintained in latching position by a spring 95, such latch lever therefore holding the controlling connections governed by the hand lever 84 in working position, against the resistance of spring 81, for an intermittent forward feed motion of the carriage and the operations

of the punch and intermittent feed mechanism. When the table 2 has completed its degree of forward feed motion dependent upon the length of the sheet to be punched, the trip member 9 engages and retracts the latch member 94 and thus releases the crank arm 87, whereupon the spring 81 will operate to project the locking bolt 79, to shift the lever 35 to reverse position, and to turn the rock shaft 58 to spread the split nut 43, thus throwing the punching and intermittent feed mechanism out of action when the table reaches the limit of its forward movement, and also throwing the reversing gearing of the friction drive mechanism into action to start the backward movement of the table and return it to starting position. When the locking bolt 79 moves upwardly as described it disposes the friction roller 78 for engagement with the arm 77, which, during a portion of the final rotation of the shaft 24, will engage the surface of the roller 78 and thus slide the clutch member 73 back to retracted position. Carried by or suitably connected with the shifting lever 35 is a pivoted trip arm or member 96 having a hooked end 97 which is arranged to lie in the path of rearward movement of the nut 43 or its support in the return movement of the table 2. When the table approaches the limit of its reverse motion to starting position the nut or its support engages the inner or straight face of hook 97 of the member 96 and trips the same to shift the lever 35 from the reverse position to its neutral position, this operation being permitted by the lost-motion connection 91-92, as previously described, the counterweight resting in the depression 38 and holding the lever in such position and the friction drive gearing out of action. On the ensuing forward movement of the nut or its support the same engages the outer beveled face of hook 97, whereby the member is tilted upward to allow the nut to pass. In the operation of the machine, the sheet to be punched is laid upon the table 2, its forward end engaged and clamped by the work clamp 6 and the clamp 7 adjusted to engage its rear edge and to bring the trip member 9 into proper position for a latch releasing action, from which it will be understood that, the crank pin 60 having been adjusted to punch the holes at the desired intervals apart, the trip member 9 will, following the final punching action, shift the latch 94 to release the crank arm 87 for the automatic operation of throwing the punch and intermittent feed mechanism out of action and effecting the automatic reversal or return of the table to starting position. From this it will be apparent that any number of holes, at any desired distance apart, may be punched according to the length of the sheet and other require- 130

ments. By the use of the intermittent feed mechanism a positive feed motion of the table to accurately spaced punching position will not only be assured, but the table and work will be held rigidly against movement between the intervals of feed motion and while the punch is in action. The machine is therefore adapted to be set for a wide variation of punching actions in punching a row or series of holes in sheet metal plates of varying lengths, and enables such work to be rapidly and conveniently performed without liability of distorting or otherwise marring or injuring the sheet. If, while on its forward motion, the table or sheet should strike any solid foreign object, damage to the apparatus or sheet will be prevented by an automatic stoppage of the working parts under such conditions. This result is secured by reason of the fact that any tendency to back pressure on the gears 34 and 35', due to sudden stoppage of the table, will result in such pressure being transmitted to the lever 35 which will tilt sufficiently to cause movement of the weight 37 and the shifting of such lever to normal or reverse position. As the drive gear 23 is constantly in motion when the machine is in use the operation of starting the mechanism into action for punching is simplified, as it requires merely the shifting of the hand lever 84 to working position.

Having thus fully described my invention, I claim:

1. In a spacing and punching machine, a traveling work supporting table, a punch, a feed mechanism for advancing the table and returning it to starting position, a second feed mechanism intermittently operable for positively governing the advancing motion of the table to spaced punching positions and maintaining it in such positions during punching periods against the driving action of the first named feed mechanism, and means for connecting said feed mechanisms with the driving element for a forward driving action of both of said feed mechanisms, said means being operative to disconnect the first-named feed mechanism from the driving element and to connect the second-named feed mechanism to the driving element for a reverse drive action to return the table to starting position.

2. In a spacing and punching machine, the combination of a traveling work supporting table, friction drive mechanism for impositively advancing the table and positively returning it to starting position, a punch, intermittent positive feed mechanism for advancing the table step by step to spaced punching positions and holding it fixed in such positions against the impositive advancing motion of the friction drive mechanism, means operating in conjunction with said positive feed mechanism for oper-

ating the punch between intervals of feed motion of the table and while said table is held in its fixed positions, and means for throwing the positive feed mechanism and punch out of action at the cessation of the 70 punching operations and reversing the said friction drive gearing for a positive reverse driving action of said friction drive mechanism on the table to return the same to starting position.

3. In a spacing and punching machine, a traveling work supporting table, a friction drive mechanism having a slip drive action on the table for urging the table forwardly and having a positive drive action on the 80 table for reversing its direction of motion to return it to starting position, a controlling positive feed mechanism for governing the forward motion of the table, moving it intermittently to predetermined punching 85 positions and fixing it against motion in such positions, a punch, means for periodically operating said positive feed mechanism, means for periodically operating the punch between intervals of operation of the feed controlling mechanism, and means for rendering the punch and positive feed mechanism inoperative at the conclusion of a predetermined number of punching actions and rendering such friction drive 90 mechanism operative for positive reverse drive action to return the work table to normal position.

4. In a spacing and punching machine, a traveling work supporting table, friction 100 drive gearing for urging the table forwardly and returning it to starting position, a punch, feed mechanism positively connected with the table for intermittently advancing said table to spaced punching positions and holding it in such positions against the forward driving action of the friction drive mechanism, means for successively and intermittently operating said positive drive mechanism and punch to advance the table 105 and actuate the punch a predetermined number of times, gearing operable for actuating the friction drive gearing for forward driving or table return motions, and means operable after a predetermined number of punching actions to throw the punch and positive feed mechanism out of operation and to reverse the direction of motion of said gearing so as to return the table to starting position.

5. In a spacing and punching machine, the combination of a traveling work supporting table, friction drive mechanism for the table, gearing for moving the table forwardly and backwardly, a punch, positive 125 feed gearing for controlling the forward motion of the table and advancing it to predetermined punching positions, means operable for adjusting the first named gearing for a forward driving action of the friction 130

- drive mechanism and throwing the punch and positive feed mechanism into action, said means also being operable for automatically adjusting the first named gearing 5 for reversing the direction of motion of the friction drive gearing to return the table to starting position and for simultaneously throwing the punch and positive feed mechanism out of action, means for holding the 10 aforesaid means in position for a forward drive action of the friction drive mechanism and successive and intermittent actions of the punch and positive feed mechanism, and means for rendering said holding means inoperative, after a predetermined number of 15 punching actions, so as to throw the punch and positive feed mechanism out of action and effect the return of the table to starting position.
- 20 6. In a spacing and punching machine, driving means, a traveling work supporting table, a punch, feed mechanism actuated by said driving means for intermittently advancing the table, holding the table fixed between intervals of motion, and operating the punch while the table is held fixed, means also driven by said driving means and independent of said feed mechanism for returning the table to starting position, and 25 means for connecting the feed mechanism to the driving means for feeding action, said means being operative for disconnecting said feeding means from the driving means and simultaneously connecting the table returning means with said driving means for 30 returning said table to starting position.
- 35 7. In a spacing and punching machine, and in combination with suitable punching mechanism, a traveling work supporting table, a drive mechanism for positively and intermittently moving the table forward to spaced punching positions, and a second drive mechanism having a slip motion with relation to the table for continuously and 40 impositively moving said table forward, said second drive mechanism being operative for continuously returning the table to normal position after the punching action.
- 45 8. In a spacing and punching machine, a traveling work supporting table, a drive shaft, a punch actuated by said shaft, intermittent table feed mechanism actuated by said shaft, a primary drive element normally free from engagement with the shaft, means for coupling said element to the shaft to effect the operation of the intermittent feed mechanism and punch in timed accord, 50 table reversing mechanism, and means operative on a prescribed movement of the table for throwing said coupling means out of action and said table reversing mechanism into action.
- 55 9. In a spacing and punching machine, a traveling work supporting table, a drive element, a drive shaft normally free from con-
- nection therewith, a punch actuated by said shaft, an intermittent table feed mechanism actuated by said shaft, means for varying the action of said intermittent feed mechanism, table reversing mechanism, a clutch 70 for connecting the shaft with the driving element, and means operative on a prescribed motion of the table for throwing said clutch out of action and said table reversing mechanism into action. 75
10. In a spacing and punching machine, a traveling work supporting table, a shaft, a driving element loose upon the shaft, a punch actuated by the shaft, mechanism also driven by the shaft for intermittently advancing the table, mechanism for retracting the table, and means for throwing said shaft into or out of driven engagement with said driving element and in the latter-named action to throw said table retracting means 80 into operation.
11. In a spacing and punching machine, a traveling work supporting table, a shaft, a drive element, a punch actuated by the shaft, intermittently operable ratchet feed mechanism actuated by the shaft for advancing the table, a clutch device for connecting the shaft with and disconnecting it from said drive element, and means embodying relatively adjustable elements comprising component parts of said ratchet feed mechanism 90 for varying the degree of table advancing motion thereof. 95
12. In a spacing and punching machine, a traveling work supporting table, a driving element, a shaft adapted to be driven from the driving element, a clutch for connecting the shaft with and disconnecting it from the driving element, a punch actuated by said shaft, intermittent feed mechanism for the 100 table also actuated by the shaft, and means for throwing said clutch device into and out of action and simultaneously throwing a part of said intermittent feed mechanism 105 into and out of action. 110
13. In a spacing and punching machine, a traveling work supporting table, a driving element, a shaft normally free from connection with the driving element, a clutch for coupling said shaft to and uncoupling it 115 from the driving element, means normally acting upon the clutch to move it into coupling position, a punch actuated by the shaft, gearing for feeding the table forward, means also actuated by the shaft for 120 intermittently operating said gearing, and means for retracting the clutch and simultaneously rendering said gearing inoperative.
14. In a spacing and punching machine, a 125 traveling work supporting table, a punch, a feed screw, a feed nut movable into and out of engagement with the screw, one of said parts being carried by the table, means for operating the punch and screw in timed 130

- accord, manually operable means for throwing the nut into connection with the screw, and automatic means for disconnecting the nut therefrom.
- 5 15. In a spacing and punching machine, a traveling work supporting table, a punch, gearing for moving the table forward comprising a screw-shaft and a nut engageable therewith, one of said parts being carried by 10 the table, intermittent feed mechanism for actuating said gearing, means for operating the punch and intermittent feed mechanism, and means for disconnecting the nut from the screw-shaft to permit independent motion of the table. 15
16. In a spacing and punching machine, a traveling work supporting table, a punch, a feed screw, a feed nut movable into and out of engagement with the feed screw, one 20 of said parts being carried by the table, rack feed mechanism for operating the screw, and means for operating the punch and rack feed mechanism in timed accord. 25
17. In a spacing and punching machine, a traveling work supporting table, a punch, intermittent feed mechanism for the table operable in timed accord with the punch and embodying a screw-shaft and a nut adapted to travel thereon, one of said parts being 30 connected with the table, and means for disengaging the elements of the gearing from each other, so as to permit movement of the table independently of said gearing. 35
18. In a spacing and punching machine, a traveling work supporting table, a punch, intermittent feed mechanism for the table operable in timed accord with the punch, and including a screw-shaft and a split nut coöperating therewith, the nut sections being 40 movable into and out of engagement with the shaft, and means for adjusting said nut sections into and out of engagement with the shaft. 45
19. In a spacing and punching machine, a traveling work supporting table, a punch, gearing for feeding the table forward comprising a screw-shaft and a sectional nut, a driving element, means for simultaneously connecting the punch and intermittent mechanism with and disconnecting the same from the driving element, and coördinate means for simultaneously moving the nut sections into and out of engagement with the screw-shaft. 50
- 55 20. In a spacing and punching machine, a traveling work supporting table, a punch, intermittent feed gearing for the table operating in timed accord with the punch, means for throwing the punch and feed 60 gearing simultaneously into and out of action, and coördinate means for simultaneously connecting the gearing with and disconnecting it from the table. 65
21. In a spacing and punching machine, the combination of a traveling work sup-
- porting table, a punch, intermittent feed mechanism for periodically advancing the table, including gear elements, a driving element, means for throwing the punch and feed mechanism into and out of connection 70 with the driving element, and means for rendering the gear elements operative for a feed action when the punch and feed mechanism are coupled to the driving element and rendering said gearing inoperative and free 75 from driving connection with the table when said punch and feed mechanism are thrown out of connection with the driving element, so as to permit the table to be moved independently of the gearing when the punch 80 and feed mechanism are idle. 85
22. In a spacing and punching machine, a traveling work supporting table, a punch, a feed screw, a feed nut engageable and disengageable from the screw, one of said parts being carried by the table, intermittent feed mechanism for operating the screw, and a common driving means for actuating the punch and intermittent feed mechanism. 90
23. In a spacing and punching machine, a traveling work supporting table, a punch, a feed screw, a feed nut engageable and disengageable from the screw, intermittent feed mechanism for operating the screw, a common shaft for operating the punch and 95 intermittent feed mechanism, a primary drive element normally disconnected from said shaft, a clutch for connecting said element with the shaft, and means for simultaneously throwing the clutch and feed nut 100 into and out of action. 105
24. In a spacing and punching machine, a traveling work supporting table, a drive shaft, a punch actuated by said shaft, a feed screw, a feed nut engageable with and disengageable from the screw, one of said parts being carried by the table, intermittent feed mechanism operated by the drive shaft, means for varying the action of said intermittent feed mechanism, a primary driving 110 element normally disconnected from the shaft, a clutch for coupling said primary drive element to the shaft, and means for simultaneously throwing the clutch and nut into and out of action. 115
25. In a spacing and punching machine, a traveling work supporting table, a drive shaft, a punch actuated thereby, a feed screw, intermittent feed mechanism actuated by the drive shaft for operating said screw, 120 a nut carried by the table and engageable with and disengageable from the screw, said nut and screw operating when engaged to positively feed the table forward, a primary drive element normally disconnected from the drive shaft, a clutch for coupling said drive element to the shaft, a friction drive 125 gearing for the table operated by said primary drive element and having an impositive forward drive action on the table and a posi- 130

tive rearward drive action thereon, and means for simultaneously throwing the nut and clutch into action for intermittently feeding the table forward and punching the

5 work between intervals of feed motion, said means being operative to simultaneously disconnect the clutch and nut to throw the same out of action and to couple the friction drive mechanism with the primary

10 drive element for a reverse drive action.

26. In a spacing and punching machine, a traveling work supporting table, a drive shaft, a punch actuated thereby, a motion transmitting shaft, gearing between said motion transmitting shaft and the table for feeding the latter forward, a crank arm carried by the drive shaft, a ratchet drive connection between said crank arm and the motion transmitting shaft for intermittently

15 operating the latter from the drive shaft, and an adjustable connection between said crank arm and ratchet mechanism for varying the degree of intermittent feed motion of the latter.

25 27. In a spacing and punching machine, a traveling work supporting table, a drive shaft, a punch actuated thereby, a motion transmitting shaft in gear with the shaft for transmitting forward motion thereto, a 30 gear loosely mounted on the motion transmitting shaft, a clutch connection between said gear and the motion transmitting shaft, a crank arm carried by the drive shaft, and a rack bar actuated by the crank arm 35 and meshing with said gear.

28. In a spacing and punching machine, a traveling work supporting table, a drive shaft, a punch actuated thereby, a motion transmitting shaft in gear with the table 40 for imparting feed motion thereto, a gear loose on the motion transmitting shaft, a clutch connection between said gear and the motion transmitting shaft, a crank arm carried by the drive shaft, a rack bar meshing 45 with the gear, and a pivotal connection between the rack bar and crank arm adjustable lengthwise of said crank arm.

29. In a spacing and punching machine, a continuously driven drive element a section 50 and drive element normally free from connection therewith, a traveling work supporting table, friction gearing for advancing and retracting the table driven by said constantly driven drive element, a punch 55 driven by the second named drive element, intermittent feed mechanism driven by the second drive element for governing and controlling the forward motion of the table to spaced punching positions, means for

60 throwing the second named drive element into and out of engagement with the first named drive element, and means for releasing the table from the intermittent feed mechanism and reversing the direction of motion of the friction drive gearing for the

return of the table to starting position upon the disconnection of the second named driving element from the first named driving element.

30. In a spacing and punching machine, a 70 traveling work supporting table, a screw-shaft supported independently of the table, a sectional nut carried by the table and mounted for movement of its sections into and out of engagement with the shaft, means 75 operative to normally urge the nut sections into engagement with the shaft, a punch, intermittently operable feed mechanism for periodically turning the screw-shaft, and means for spreading the nut sections to free 80 them from engagement with the shaft and releasing them to permit them to move into engagement with the shaft.

31. In a spacing and punching machine, a 85 traveling work supporting table, a continuously operated driving element, an actuating shaft, a punch actuated thereby, intermittent feed mechanism operable by the shaft, said mechanism including a screw-shaft and a sectional nut, means for normally urging the nut sections into engagement with the screw-shaft, means for spreading the nut sections, a clutch device for connecting the actuating shaft with and disconnecting it from the constantly movable drive 95 element, a controller for the clutch, and means for simultaneously operating said controller and the nut spreading device.

32. In a spacing and punching machine, a traveling work supporting table, drive gearing impositively connected with the table for moving the same forwardly and rearwardly, drive gearing adapted to be positively connected with the table for controlling the forward motion thereof, advancing said 100 table to spaced punching positions and holding the table in such positions, a continuously operating primary drive element, a punch, intermittent feed mechanism for periodically actuating the second named 105 drive gearing, means for connecting said drive element with and disconnecting it from the punch and intermittent feed mechanism, a shifting device governed by the aforesaid means for reversing the direction of motion 110 of the first named drive mechanism, and means controlled by the movement of the table to govern the aforesaid means for throwing the punch and positive drive gearing out of action at the limit of forward 115 movement of the table and actuating said shifting device to effect the return of the table to starting position.

33. In a spacing and punching machine, a 120 traveling work supporting table, drive gearing in frictional engagement with the table for advancing and retracting the same, intermittently operated positive feed gearing governing the forward motion of the table to spaced punching positions, a punch, means 125 130

for setting the positive drive gearing and punch into operation for successive spacing and punching actions, and means for throwing the positive drive gearing and punch out 5 of action and rendering the friction drive gearing operative to reverse the direction of travel of the carriage.

34. In a spacing and punching machine, a traveling work supporting table, a punch, a 10 feed mechanism for advancing the table and returning it to starting position, a second feed mechanism intermittently operable for positively governing the advancing motion of the table to spaced punching positions 15 and maintaining it in such positions during punching periods against the driving action of the first named feed mechanism, means for throwing the punch and second named feed mechanism into action for successive 20 table feeding and punching actions, and means operating at a proper time period for throwing the punch and second named feed mechanism out of action and governing the first named feed mechanism to return 25 the table to starting position.

35. In a spacing and punching machine, a traveling work supporting table, a shaft, a driving element loose upon the shaft, a punch actuated by the shaft, a feed screw, a 30 nut carried by the table and engageable with and disengageable from the screw, ratchet mechanism also driven by the shaft for intermittently rotating said screw, and means for simultaneously throwing the shaft into 35 and out of driven engagement with said driving element and the nut into and out of driven engagement with the feed screw.

36. In a spacing and punching machine, a traveling work supporting table, a punch, 40 means for successively feeding the table forward step by step and operating the punch between such step by step motions, a table drive mechanism reversible to drive the table backward and having a forward 45 slip drive action on the table controlled by said step by step feeding means, and means for rendering said punch and step by step feeding means inoperative after a predetermined number of punches have been made 50 and reversing said table drive mechanism for a table reversing action.

37. In a spacing and punching machine, a traveling work supporting table, a punch, 55 intermittent feed mechanism for the table, driving means, an automatic clutch for connecting the punch and intermittent feed mechanism with the driving means, an automatic device for retracting and holding the clutch normally inactive, a latch for 60 holding said device in clutch releasing position, and means operated by the table for releasing said latch.

38. In a spacing and punching machine, a traveling work supporting table, a punch, a

screw-shaft, a nut having sections movable 65 into and out of engagement with the shaft, intermittent feed mechanism for operating the shaft, driving means, an automatic clutch for connecting the punch and intermittent feed mechanism with the driving 70 means, an automatic device for retracting and holding the clutch normally inactive, a controlling connection between said device and the nut for opening and closing the latter, a latch for holding said device in clutch 75 releasing and nut closing position, and means operated by the table for releasing said latch.

39. In a spacing and punching machine, a traveling work supporting table, a punch, a 80 screw-shaft, a nut having sections movable into and out of engagement with the shaft, intermittent feed mechanism for operating the shaft, driving means, an automatic clutch for connecting the punch and intermittent 85 feed mechanism with the driving means, an automatic device for retracting and holding the clutch normally inactive, a controlling connection between said device and the nut for opening and closing the latter, a latch for holding said device in clutch 90 releasing and nut closing position, relatively adjustable work clamps carried by the table, and a contact carried by one of said work clamps for releasing said latch.

40. In a spacing and punching machine, a traveling work supporting table, a punch, friction feed mechanism for the table, a shifter adjustable to positions to adapt said friction feed mechanism to drive the table 100 forward and backward, a screw-shaft, a nut having sections movable into and out of engagement with the shaft, intermittent feed mechanism for operating the shaft, an automatic clutch for connecting the punch and 105 intermittent feed mechanism with the driving means, an automatic device for retracting the clutch and holding the same normally inactive, a controlling connection between said device and the nut and shifter, a latch for holding said device in position to 110 release the clutch, close the nut and dispose the shifter for a forward driving action of the friction drive mechanism, and means operated by the table to release said device 115 for action to effect the retraction of the clutch, spreading of the nut and movement of the shifter to cause the friction drive mechanism to return the table to starting position.

41. In a spacing and punching machine, a traveling work supporting table, a driving shaft, a punch actuated by said shaft, a positive intermittent table feed mechanism also actuated by said shaft, a primary drive 125 element normally free from connection with the shaft, a friction feed mechanism for feeding the table forwardly and back-

wardly, gearing for driving said friction feed mechanism, and means for simultaneously connecting the intermittent feed mechanism and friction feed mechanism with the primary driving element for a forward feed motion and for operating the punch at prescribed periods, and for simultaneously disconnecting the punch and in-

termittent positive feed mechanism from the primary driving element and connecting the friction feed mechanism with said primary driving element for a reverse table driving action.

In testimony whereof I affix my signature.

COLUMBUS K. LASSITER.
